BABY CRIB TRAY

Jeanne E. Spiro, North Hollywood, Calif.
Application June 6, 1957, Serial No. 46,508

Term of patent 14 years
(Cl. D5—5)

The back of the baby crib tray design shown in Figures 1 and 2 is plain and unornamented.

I claim:

The ornamental design for a baby crib tray as shown and described.
